Primary Examiner — Brian N Vinson(74) *Attorney, Agent, or Firm* — Simpson & Simpson, PLLC(57) **CLAIM**

The ornamental design for a mounting shelf with concealment means, as shown and described.

DESCRIPTION

FIG. 1 is a front perspective view of a mounting shelf with concealment means of the present invention;

FIG. 2 is a front elevational view of the invention shown in FIG. 1;

FIG. 3 is a rear elevational view of the invention shown in FIG. 1;

FIG. 4 is a left side elevational view of the invention shown in FIG. 1;

FIG. 5 is a right side elevational view of the invention shown in FIG. 1;

FIG. 6 is a top plan view of the invention shown in FIG. 1; and, FIG. 7 is a bottom plan view of the invention shown in FIG. 1. The broken line illustrations shown in the drawings depict environmental subject matter only and form no part of the claimed design.
